TABLE

James E. Jones and Edward P. Stevens, Toledo, Ohio, assignors to The Hettrick Manufacturing Company, Toledo, Ohio, a corporation of Ohio

Application December 27, 1955, Serial No. 39,484

Term of patent 14 years

(Cl. D33—14)

FIG. 1.

FIG. 3.

FIG. 2.

We claim:

The ornamental design for a table, as shown.
